WILLIAM R. RAY.

BY Chas. E. Townsend.

ATTORNEY

UNITED STATES PATENT OFFICE.

WILLIAM R. RAY, OF SAN FRANCISCO, CALIFORNIA.

HIGH-PRESSURE AUTOMATIC BURNER GOVERNOR.

1,425,338.

Specification of Letters Patent. Patented Aug. 8, 1922.

Application filed January 23, 1920, Serial No. 353,478. Renewed January 18, 1922. Serial No. 530,230.

To all whom it may concern:

Be it known that I, WILLIAM R. RAY, a citizen of the United States, residing at the city and county of San Francisco and State of California, have invented a new and useful Improvement in High-Pressure Automatic Burner Governors, of which the following is a specification.

This invention relates to an oil burner and especially to an automatic governor control whereby the quantity of oil delivered to the burner is regulated by variations in steam pressure.

One of the objects of the present invention is to provide an automatic burner governor whereby the quantity of oil delivered to the burner may be automatically regulated, and especially to provide a steam actuated diaphragm valve and a cooperating relief valve whereby the delivery of oil to the burner is so regulated that a small fire will be maintained when a predetermined boiler pressure is reached, and a large fire produced when the boiler pressure is lower.

Another object of the invention is to provide manually actuated means for varying the quantity of oil delivered either when the fire is small or large thus increasing or decreasing the size of the fire as required.

Another object of the invention is to provide an automatic governor control of the character described which is especially adapted to be employed in conjunction with an oil delivering pump having a constant delivery.

Further objects will hereinafter appear.

The invention consists of the parts and the construction, combination and arrangement of parts as hereinafter more fully described and claimed, having reference to the accompanying drawings, in which—

Fig. 1 is a front view of the burner showing the application of the automatic governor.

Fig. 2 is a plane section of the diaphragm actuated valve taken on line 2—2, Fig. 3.

Fig. 3 is a side elevation of the diaphragm actuated valve with parts broken away to more clearly illustrate the construction.

Referring to the drawings in detail, A indicates in general an oil burner, the burner employed in the present instance being of the rotary atomizing type as shown in my former Patent No. 1,285,376, issued November 19, 1918, and entitled "Oil burner." A burner of this character consists of a rotary atomizing

cup which is rotated by means of an electric motor B. Oil is delivered to this cup through a pipe 2 which extends through a hollow motor shaft. Air is also delivered and is in this instance supplied by means of a fan inclosed within a housing 3, said fan being secured on the motor shaft and rotating in unison with the atomizing cup. The oil supplied to the cup is delivered by means of a gear pump 4. This pump is driven from the motor shaft and is provided with an intake and an outlet connection such as shown at 5 and 6 respectively. The intake connection is connected by means of a pipe 7 with a tank of oil or other suitable source of supply, and the oil discharged by the pump through the outlet 6 is delivered to a jacket passage 8 formed exterior of the motor housing. The oil after passing through the housing discharges at 9 into a pipe 10 which is connected with a vertically disposed pipe 11. This pipe is connected with a return pipe line 12 by means of a pipe 13 to permit any surplus amount of oil delivered by the pump 4 to be returned to the tank. The oil required by the burner is by-passed from the pipe 11 through a pipe 2 which is connected with a valve 15 which regulates the quantity of oil delivered. Mounted on the return pipe line 12 is a pressure gauge 16, a diaphragm actuated valve C and a relief valve D. The diaphragm actuated valve consists of a housing 17, in the upper portion of which is mounted a diaphragm 18. This diaphragm is held on top of the casing 17 by means of a head member 19 and a pressure chamber 20 is thereby formed above the diaphragm, the function of which will hereinafter be described. Connected with the head member 19 is a pipe 21, the opposite end of which is connected with the steam dome of the boiler as indicated by 21^a. Positioned below the diaphragm is a spring 22 and adapted to regulate the tension of said spring is an adjusting nut 23. Attached to the lower end of the casing 17, or formed integral therewith, is a valve casing 24, and mounted in said casing is a valve 25, which is connected with the diaphragm 18 by means of a centrally disposed rod 26. The housing 24 is divided into two chambers 27 and 28. The surplus oil discharging into the pipe 12 enters the chamber 27 and its flow into chamber 28 with connected pipe 30 is regulated by means of the valve 25 and also by means of a by-pass valve 31. This valve, as

shown in Fig. 2, is held against its seat by means of a spring 32, the tension of which may be regulated by means of a screw 33. The valves 25 and 31 therefore serve the function of creating a back pressure on the return line 12 and this pressure is regulated, first, by the relief valve 31, and secondly, by the automatic actuated valve 25. Cooperating with the valves 25 and 31 is the relief valve D. This valve is somewhat similar in construction to the valve 31 inasmuch as it is held against its seat by means of a spring the tension of which is regulated by a screw and a hand wheel 36. The valves 25 and 31 serve the function of automatically controlling the large fire, while the relief valve D serves the function of regulating the small fire.

For the purpose of clearly illustrating the function of the valves 25 and 31, and the valve D, it should first of all be realized that the pump employed has a constant delivery, that is the pump is driven directly from the motor shaft and as the speed of the motor is constant the speed of the pump will also be constant, hence a uniform quantity of oil will be travelling through the pipes. Secondly, we will assume that it is desired to maintain a pressure of 40 pounds when a large fire is required, and that pressure of 15 pounds will be required when the boiler is operating under a small fire. Further that the diaphragm valve C is so adjusted that it will not open the valve 25 until a steam pressure of 180 pounds is obtained. When the burner is operating under a large fire and the pressure in the boiler gradually increases until 180 pounds is attained, it should be obvious that the pressure in the chamber 20 exerted upon the diaphragm 18 will be sufficient to overcome the tension of the spring 22. The diaphragm 18 will under this condition yield a sufficient distance to permit the valve 25 to open, the returning oil will thus find a free escape through the valve casing 24 and the only resistance imposed upon the free return of the oil to the tank will be the relief valve D. This is, however, regulated so that a back pressure of 15 pounds will be maintained on the return line and the surplus oil will therefore be maintained under a pressure of 15 pounds, said pressure being that required for a small fire. The diaphragm valve 25 will remain open as long as the steam pressure in the boiler remains at 180 pounds. It will, however, close the moment the boiler pressure drops and the pressure in the return line 12 will then immediately build up to 40 pounds as valve 25 is closed and the only escape possible for the returning oil will therefore be through the valve controlled passage 31. This is, however, set for 40 pounds pressure and the oil on the return line will therefore build

up until 40 pounds pressure is obtained as it cannot escape the by-pass valve 31 until this pressure is obtained. The size of the fire will therefore increase as the pressure builds up and the maximum size fire is obtained when the pressure of 40 pounds is reached. The large fire will continue until the maximum boiler pressure is again reached and the cycle of operation will thus be repeated.

If it is desired to produce a still larger fire, it will only be necessary to adjust the screw 23 or the tension of the spring 32, so that the back pressure on the return line will be increased, for instance, to 50 or 60 pounds, or to any pressure desired, this adjustment being provided for the purpose of varying the size of the large fire. If it is desired to increase the size of the small fire, it will only be necessary to increase the tension of the spring in the relief valve D so that the back pressure obtained will be greater than 15 pounds, and if it is desired to decrease the size of the small fire a reverse adjustment is resorted to.

From the foregoing description it can be seen that I have provided means for automatically maintaining a large or small fire. Secondly, that manual means are provided for increasing or decreasing the size of either the large fire or the small fire, or both. This is of considerable importance as the steam generating capacity of a boiler may thus be varied for the load required or as other conditions may demand.

While the automatic burner control is here shown as employed in conjunction with a burner of the rotary atomizing type, it is obvious that any other suitable form of burner may be employed. Similarly varying changes may be made within the scope of the appended claims without departing from the spirit of the present invention.

Having thus described my invention, what I claim and desire to secure by Letters Patent is—

1. The combination with an oil burner and a pump for delivering oil thereto, of an oil delivery and return pipe line connected with the pump and the burner, a valve on the return line adapted to open or close the flow of oil therethrough and a by-pass valve co-operating therewith for maintaining a back pressure on the return line when the valve is closed.

2. The combination with an oil burner and a pump for delivering oil thereto, of an oil delivery and return pipe line connected with the pump and the burner, a valve on the return line adapted to open or close the flow of oil therethrough, a by-pass valve co-operating therewith for maintaining a back pressure on the return line when the valve is closed, and means for adjusting the by-pass valve to vary the back pressure.

3. The combination with an oil burner and a pump for delivering oil thereto, of an oil delivery and return pipe line connected with the pump and the burner, a valve on the return line adapted to open or close the flow of oil therethrough, a by-pass valve cooperating therewith for maintaining a back pressure on the return line when the valve is closed, and pressure actuated means for opening or closing the first named valve. 75
4. The combination with an oil burner and a pump for delivering oil thereto, of an oil delivery and return pipe line connected with the pump and the burner, a valve on the return line adapted to open or close the flow of oil therethrough, a by-pass valve cooperating therewith for maintaining a back pressure on the return line when the valve is closed, pressure actuated means for opening or closing the first named valve, and means for adjusting the by-pass valve to vary the pressure. 80
5. The combination with an oil burner and a pump for delivering oil thereto, of an oil delivery and return pipe line connected with the pump and the burner, a valve on the return line adapted to open or close the flow of oil therethrough, a by-pass valve cooperating therewith for maintaining a back pressure on the return line when the valve is closed, and a relief valve on the return line adapted to produce a back pressure on the return line independent of the by-pass valve. 95
6. The combination with an oil burner and a pump for delivering oil thereto, of an oil delivery and return pipe line connected with the pump and the burner, a valve on the return line adapted to open or close the flow of oil therethrough, a by-pass valve cooperating therewith for maintaining a back pressure on the return line when the valve is closed, a relief valve on the return line adapted to produce a back pressure on the return line independent of the by-pass valve, and means for regulating the relief valve to increase or decrease the back pressure produced thereby. 100
7. The combination with a boiler and an oil burner cooperating therewith, of a pump adapted to deliver oil to the burner, a return pipe line connected with the burner, a valve on said line adapted to open or close the flow of oil through the return line, a diaphragm actuated by steam pressure in the boiler adapted to open or close the valve, adjustable means engageable with the diaphragm for regulating the movement thereof, and a by-pass valve connected with the pressure actuated valve adapted to create a back pressure on the return line independent of the pressure actuated valve. 115
8. The combination with a boiler and an oil burner cooperating therewith, of a pump adapted to deliver oil to the burner, a return line connected with the pump and the burner, means on the return line for producing a constant back pressure when a small 120
9. The combination with a boiler and an oil burner cooperating therewith, of a pump adapted to deliver oil to the burner, a return pipe line connected with the burner, a valve on said line adapted to open or close the flow of oil through the return line, a diaphragm actuated by steam pressure in the boiler adapted to open or close the valve, adjustable means engageable with the diaphragm for regulating the movement thereof, a by-pass valve cooperating with the pressure actuated valve adapted to create a back pressure on the return line independent of the pressure actuated valve, means for adjusting the position of the by-pass valve to vary the back pressure on the return line independent of the pressure actuated valve, and a relief valve on the pipe line adapted to create a back pressure on the return line independent of the by-pass valve and the pressure actuated valve. 130
10. The combination with a boiler and an oil burner cooperating therewith, of a pump adapted to deliver oil to the burner, a return pipe line connected with the burner, a valve on said line adapted to open or close the flow of oil through the return line, a diaphragm actuated by steam pressure in the boiler adapted to open or close the valve, adjustable means engageable with the diaphragm for regulating the movement thereof, a by-pass valve cooperating with the pressure actuated valve adapted to create a back pressure on the return line independent of the pressure actuated valve, means for adjusting the position of the by-pass valve to vary the back pressure on the return line independent of the pressure actuated valve, a relief valve on the pipe line adapted to create a back pressure on the return line independent of the by-pass valve and the pressure actuated valve, and means for regulating the position of the relief valve to increase or decrease said back pressure. 125
11. The combination with a boiler and an oil burner cooperating therewith, of an oil pump adapted to deliver oil to the burner, a return line connected with the pump and the burner, means on the return line for producing a constant back pressure when a small 130

fire is required, and means actuated by the steam pressure in the boiler for producing a back pressure on the return line in excess of the first named means to produce a large

5 fire under the boiler.

12. The combination with a boiler and an oil burner cooperating therewith, of an oil pump adapted to deliver oil to the burner, a return line connected with the pump and

10 the burner, a relief valve on the return line adapted to maintain a constant back pressure thereon, and a diaphragm actuated valve on the return line adapted to produce an increased back pressure when the pressure in

15 the boiler is below a predetermined pressure.

13. The combination with a boiler and an oil burner cooperating therewith, of an oil pump adapted to deliver oil to the burner, a return line connected with the pump and

the burner, a relief valve on the return line 20 adapted to maintain a constant back pressure thereon, and a diaphragm actuated valve on the return line adapted to produce an increased back pressure when the pressure in the boiler is below a predetermined pressure, 25 said diaphragm actuated valve being automatic in operation and adapted to reduce the pressure to that maintained by the relief valve when the pressure in the boiler reaches a predetermined pressure.

30 In testimony whereof I have hereunto set my hand in the presence of two subscribing witnesses.
